BINDER

Andrew Kowalsky, Perdido Beach, Ala., assignor to International Harvester Company, a corporation of New Jersey

Application February 23, 1942, Serial No. 431,949

5 Claims. (CL. 56—449)

This invention relates to a binder and particularly to a binder for binding grain or corn. Still more particularly the invention pertains to bundle-forming mechanism for a binder.

In a grain binder, for example, the usual construction includes a binder deck and a breastplate disposed in spaced apart relation and adapted to receive therebetween grain to be formed into a bundle. The binding mechanism includes knotter mechanism operable when the bundle has attained the proper size, the bundle being thereafter discharged by release of the usual trip mechanism. The trip mechanism includes an arm which serves to support the bundle and which is releasable when the bundle reaches the proper size. In the usual binder construction, the trip or release arm does not entirely enclose the space between the deck and the breastplate, with the result that portions of the grain escape over the end of the release arm. This disadvantage is especially pronounced because the space through which the grain escapes is in close proximity to the knot-tying mechanism. Consequently, it is difficult at all times for the binder to form and discharge satisfactory bundles.

The principal object of the present invention is to provide an improved retaining means which cooperates with the usual bundle-forming mechanism and which serves to insure the proper formation of bundles.

It is an important object of this invention to provide means by which the retaining means is operated by the binding mechanism in timed relationship so that the means is in bundle-retaining position during formation of the bundle and is released upon discharge of the bundle.

Another object is to provide the retaining means in the form of an arm pivotally carried by the breastplate and having a portion adapted to cooperate with the usual trip or presser arm of the binder to completely enclose the space between the breastplate and the deck.

Another object is to provide cam means operable by a rotating part of the binder, preferably the discharge arm shaft, for actuating the retaining means.

The foregoing and other important objects of this invention will become readily apparent from the following detailed description and accompanying sheet of drawings, in which:

Figure 1 is a side elevational view partly in section showing the bundle-forming mechanism of a binder of the usual type;

Figure 2 is a view similar to Figure 1 but show-

ing the parts in position after the bundle has been discharged;

Figure 3 is an elevational view of a portion of the binder showing generally the driving mechanism therefor;

Figure 4 is a top plan view of the bundle-forming mechanism of the binder of this invention; and

Figure 5 is a fragmentary view in perspective showing parts beneath the binder deck.

As previously stated, the invention is particularly applicable to machines of the corn or grain-binding type, but it will be appreciated that the mechanism provided by the invention may be suitably utilized in other instances.

For the purposes of illustration and disclosure, the bundle-forming mechanism of a conventional grain binder has been selected and only those portions of the binder deemed necessary for adequate disclosure have been illustrated and will be described.

As shown in Figures 1 and 2, the reference character 5 designates the binder deck. A breastplate, indicated at 6, is disposed in spaced relation with respect to the deck 5. In the case of a grain binder, a shaft 7 (Figure 3) is journaled below and transversely of the deck 5. This shaft constitutes the usual packer arm shaft which carries a plurality of packer arms, only one of which is shown at 8. A needle shaft 10 parallels the packer shaft 7, carries the twine 35 and has its outer end formed with a crank 11. A third shaft 12 parallels the needle shaft 10 below the deck 5. This shaft carries for rotation therewith a forwardly extending member 13, to which is rigidly secured an upstanding trip or presser arm 14. This arm extends through a slot in the deck 5 and its free end is spaced slightly from the proximate surface of the breastplate 6. The needle shaft 10 carries a needle 15 which may be of conventional design.

The breastplate 6 carries at its side opposite the side facing the deck 5 a supporting housing 16 in which is journaled a transverse shaft 17. The housing 16 and its associated sleeve portion 18 are further supported from the breastplate 6 by a brace member 19. The shaft 17 constitutes the usual discharge arm shaft and carries a discharge arm 20. Knot-tying mechanism, which may be of usual design as generally indicated at 21, is provided in the usual location on the breastplate 6.

As shown in Figure 3, the main frame of the binder includes a portion serving as a housing 22. This housing contains suitable gearing, not

shown, for driving a gear wheel 23 on the discharge arm shaft 17. The packer arm shaft 7 carries a clutch member 24. The trip arm shaft 12 carries a latch member 25 engageable with a pawl 26 of the clutch member 24. During the formation of the bundle, the parts are in the positions shown in Figures 1 and 3. The latch 25 maintains the pawl 26 in disengaged position so that the clutch member 24 is prevented from rotating with the packer shaft 7. When the bundle reaches the proper size and is ready for discharge, the pressure created by the added size and weight of the bundle releases the trip arm 14. As best shown in Figure 5, movement of this arm 14 is followed by slight rotation of the trip arm shaft 12, which raises the latch 25 away from the clutch pawl 26. The clutch member 24 then rotates and, through the mechanism in the housing 22, drives the gear wheel 23, thus rotat- 15 ing the discharge arm shaft 17. The crank 11 at the outer end of the needle shaft 10 is connected to one end of a connecting rod 27, the other end of this rod being connected to the gear wheel 23. Upon rotation of the gear wheel 23, the connecting rod 27 effects operation of the needle shaft 10, the needle 15 and the knot-tying means 21 then functioning in the usual manner to bind the bundle, after which the trip arm 14 is moved to the position shown in Figure 2. Rotation of the discharge arm shaft 17 is such that the discharge arm 20 engages the bundle and discharges the same from the deck 5. The gear wheel 23 is associated in the usual manner with means, generally indicated at 28, for restoring the latch 25 to its original position for maintaining the clutch pawl 26 out of engagement with the packer shaft 7. The mechanism and operation just described are conventional in the usual grain binder and are well understood by those versed in the art, and the general description thereof has been set forth merely for the purpose of providing an adequate background for the disclosure of the present invention.

As stated previously, the end of the trip arm 14 is spaced a slight distance from the proximate surface of the breastplate 6. It will be seen, upon examination of the drawing, that this space is in close proximity to the knot-tying means 21. As also stated previously, it has been found in previous constructions that portions of the grain or other material being bound had a tendency to escape through this space. The possibility of this result is especially illustrated in Figure 1, wherein a dotted circle designated by the numeral 34 represents a bundle being formed between the deck and breastplate. According to the present invention, means is provided for eliminating the difficulty just described.

In a preferred form of the invention the retaining means takes the form of an arm or member 29 pivoted at one end at 30 on the breastplate 6. In normal position this arm parallels the breastplate and has at its free end an angular portion 31 which extends toward the deck 5. In particular, the portion 31 combines with the trip arm 14 to completely enclose the space between the deck 5 and the breastplate 6. An intermediate portion of the arm carries a roller 32. This roller is engaged in normal position of the arm by a cam member 33 carried by and for rotation with the discharge arm shaft 17. The cam thus provides means for maintaining the retaining arm in normal or retaining position, and, upon rotation of the cam, release

of the arm is effected, as will hereinafter more fully appear.

During the operation of the binder, as equipped with the improved retaining means, the parts are 5 in the positions illustrated in Figure 1. In such instance the angular portion 31 of the arm 29 is cooperating with the trip arm 14 to provide means that properly retain the bundle to be formed. It will be noted that the roller 32 on 10 the arm 29 is engaged by a high spot on the cam 33, so that the arm is securely held in normal or bundle-retaining position. After the bundle has been formed, the bundle-forming mechanism operates in the manner previously 15 described. Upon rotation of the discharge arm shaft 17 for the discharging of the completed bundle, the cam 33 rotates and a low spot on the cam is presented to the roller 32, thus effecting or permitting movement of the arm 29 out of the path of the discharged bundle. Upon completion of the discharging operation, the arm 29 returns to position as the other binder parts are also restored to their starting positions.

It will be noted that the angular portion 31 25 on the arm 29 effectively closes the space between the free end of the trip arm 14 and the proximate surface of the breastplate 6. Thus, means is provided for preventing the escape of portions of the grain or like material through the opening that formerly existed, with the result now that 30 the grain or the material being bound is properly held in place so that satisfactory bundles are insured. The driving means, comprising the cam 33 and roller 32, effectively controls the movement of the retaining arm 29.

The preferred form of the invention illustrated has been designed primarily as an attachment for a conventional binder, and it will be seen that this attachment may be readily installed without seriously altering the existing binder construction. Other advantages in the design and functioning of the mechanism will 40 be apparent to those skilled in the art.

It will be understood, of course, that only a 45 preferred embodiment of the invention has been disclosed and that numerous modifications and alterations may be made therein without departing from the spirit and scope of the invention as defined in the appended claims.

50 What is claimed is:

1. For a binder having bundle-forming mechanism including a deck and a breastplate spaced apart and adapted to receive a bundle therebetween, a presser arm alternately extended and retracted through said deck, and an intermittently driven discharge arm movable to discharge a completed bundle; bundle-retaining means comprising a retaining member and the said presser arm; means mounting the member on the breastplate for swinging movement between two 55 positions; said member including a portion adapted to extend, in one position of the member, at least partially across the space between the deck and breastplate and complementing the presser arm for entire coverage of said space to retain the bundle being formed; and cam means mounted with and operated by the intermittent drive of the discharge arm and having high and low portions engageable with the retaining member to respectively maintain the member in bundle-retaining position and to effect release of the member from said position upon movement of the discharge arm to discharge the bundle.

2. For a binder having bundle-forming mechanism including a deck and a breastplate spaced

apart and adapted to receive a bundle therebetween, a discharge arm movable to discharge a completed bundle, and a releasable presser arm extending from the deck toward the breastplate and closing only a portion of the space between the deck and breastplate: bundle-retaining means comprising a member having a portion closing the remainder of the space between the deck and breastplate to cooperate with the presser arm in retaining a bundle; means mounting the member for movement away from retaining position; and cam means unitarily mounted with and operated by the discharge arm and engaging said bundle-retaining means whereby a portion of said cam maintains the member in bundle-retaining position and another portion effects the release of the member from said position upon movement of the discharge arm to discharge the bundle.

3. For a binder having bundle-forming mechanism including a deck and a breastplate spaced apart and adapted to receive a bundle therebetween, and a discharge arm carried for rotation by a shaft transversely of the breastplate: bundle-retaining means comprising a member having a portion extending at least partially across the space between the breastplate and deck for retaining the bundle being formed; means mounting said member for movement away from retaining position; a cam affixed to said discharge arm shaft and having a continuous surface engageable with the said member, whereby when the discharge arm is stationary the said member is in a bundle-retaining position and upon rotation of the said discharge arm shaft the member is released permitting discharge of the bundle.

4. For a binder having bundle-forming mechanism including a deck and a breastplate spaced apart and adapted to receive a bundle therebetween, a shaft rotatably carried by the breastplate and extending transversely thereof, a dis-

charge arm carried by the shaft for rotation therewith to discharge a bundle from the deck: bundle-retaining means comprising an arm pivoted at one end on the breastplate for movement toward and away from the deck, said arm including at its other end an angular portion extending toward the deck and in part closing the space between the deck and breastplate to retain a bundle on the deck, said portion being normally disposed in retaining position during formation of a bundle; a cam immovably mounted relative to said discharge arm shaft, the said cam engaging said retaining arm, whereby upon actuation of said shaft and said cam the retaining arm is adapted to automatically switch from a bundle-retaining position to an out of the way released position.

5. For a binder having bundle-forming mechanism including a deck and a breastplate spaced apart and adapted to receive a bundle therebetween, a shaft rotatably carried by the breastplate and extending transversely thereof, a discharge arm carried by the shaft for rotation therewith to discharge a bundle from the deck: bundle-retaining means comprising an arm pivoted at one end on the breastplate for movement toward and away from the deck, said arm including at its other end an angular portion extending toward the deck and in part closing the space between the deck and breastplate to retain a bundle on the deck, said angular portion being normally disposed in retaining position during formation of a bundle; cam means carried by and rotatable with the discharge arm shaft and engageable with the angular portion of the retaining arm for alternately maintaining said arm in and out of retaining position, said cam being formed to effect release of said arm upon rotation of said shaft to discharge a bundle.
